UNITED STATES PATENT OFFICE

2,387,540

FLUID-PRESSURE ENGINE

Frank Edward Swain, Ewell, England

Application October 8, 1943, Serial No. 505,543
In Great Britain November 11, 1942

7 Claims. (Cl. 123—50)

This invention relates to a fluid-pressure engine, for example, an internal-combustion engine or a compressor, of the kind of which the cylinders, coacting with pistons, have radially-extending axes. The cylinders may be arranged in a circle with their axes in a plane at right angles to the crankshaft axis, or in two or more parallel circles. Alternatively, they may be arranged side-by-side in a single line or in two or more lines.

Objects and advantages of the invention will be understood from the following description in which reference is made to the accompanying drawings.

According to the invention, one of each of the said coacting members (piston or cylinder) is connected to a Z-type crankshaft, the axes of the cylinder, of the crankshaft, and of the inclined pin thereof, all meeting at a point. If the said coacting member be connected with one end of the inclined pin, it will be completely reciprocated once for each revolution of the crankshaft. If it be connected to a lug extending from the centre of the adjacent side of the inclined pin it will be completely reciprocated twice for each crankshaft revolution. The pistons may be stationary, the cylinders being connected to the crankshaft, instead of the more usual arrangement of reciprocating piston and stationary cylinder. Alternatively each of the coacting members (piston and cylinder—the latter formed as a sleeve valve if desired) may be connected to opposite ends of the inclined crankpin. Or one of them may be connected to the near side of the centre of the pin (for double reciprocation) and the other to one end thereof.

In the accompanying diagrammatic drawings:

Figure 1 is a sectional elevation of a flat-twin internal-combustion engine according to the invention;

Figure 2 is a part-sectional elevation of a double V-twin internal-combustion engine also in accordance with the invention;

Figure 3 is a cross-section of the engine of Figure 2;

Figure 4 is a sectional elevation of another form of internal-combustion engine, according to the invention, with the piston shown in elevation; and

Figure 5 is a sectional elevation, rather similar to that of Figure 4, of yet another form of internal-combustion engine according to the invention.

The same reference numerals are used through-

out the various figures as far as possible to denote similar parts.

In the construction of Figure 1, 11 represents the inclined pin of a Z-type crankshaft 12 having a sleeve 13 journalled on the pin, and in this case opposite ends of the sleeve carry lugs 14, 14 connected by connecting rods 15, 15 to pistons 16, 16 respectively reciprocable in diametrically-opposite cylinder bores. The engine in question is a two-stroke engine with crank case compression, having transfer passages 17, 17 leading from the crank case to the cylinder bores (the inlet to the crank case is not shown), whilst the ports 18, 18 are exhaust ports. The cylinders are, of course, stationary, the cylinder heads being indicated by the chain lines 19. The pistons work in unison, and the chain lines 15a represent the positions of the connecting rods when the pistons are at in-centre. It will be observed that the axis of the cylinder marked X, the axis of the crankshaft marked Y and the axis of the inclined pin 11 marked Z all meet at a point, as shown in Figure 1.

It will be evident that during one complete revolution of the crankshaft each piston is completely reciprocated (up and down) once.

Figures 2 and 3 show a four-cylinder two-stroke engine with two pairs of radial, side-by-side cylinders 21, 22, indicated by chain lines, arranged with their axes in two planes at right-angles to one another. The engine is, in fact, a double V-twin.

In the present instance, the coacting members include pistons 16 which are stationary and reciprocating sleeve-valve cylinders 24 which are worked from lugs at the ends of sleeves 13 on the inclined portions 11, 11 of the crankshaft. The two inclined portions 11, 11 are in this instance essentially a single inclined portion with an intermediate bearing portion. The sleeve-valve cylinders 24 of each pair (21 or 22) of stationary cylinders, being connected to opposite ends of the double inclined portion, are 180° out of step, as shown clearly in Figure 2. Each is reciprocated completely only once for each crankshaft revolution.

The pistons in this case may be water-cooled, 26 (Figures 2 and 3) indicating outlet passages and 27 (Figure 3) an inlet passage.

The left-hand sleeve-valve cylinder 24 in Figure 2 is shown at its in-centre position, in which ignition is occurring and the power stroke beginning. The right-hand cylinder 24 of Figure 2 is shown at its out-stroke position in which its inlet ports 29 are aligned with corresponding

ports leading to passages 30 in the stationary cylinder block and through which the charge may be introduced. 31 represents an exhaust port in a sleeve-valve cylinder 24.

In the present instance, the axially-outer ends 33 of the sleeve-valve cylinders 24 serve as compressor pistons, to compress the charge and deliver it to a receiver, connected with the passages 30 whence it is returned to the interior of the sleeve-valve cylinders through the inlet ports 29 when the sleeve-valve cylinders reach the out-centre positions and the ports are placed in the open position. The ports 29 and 31, it will be observed, trace out a complete ellipse during each crankshaft revolution and very satisfactory porting can be provided by a suitable shaping of the ports, the opening of the ports being controlled mainly by the rotary movement of the sleeve-valve cylinders 24.

In the construction of Figure 4, as applied to a multiple-row, radial engine (only one pair of coating members being shown in detail), both the piston 16 and the cylinder 24 adapted as a sleeve valve are respectively connected by connecting rods 15 with lugs on the same side and at opposite ends of the sleeve 13 journalled upon the inclined portion 11 of the crankshaft 12. Thus, the coating piston and cylinder are oppositely reciprocated, each again effecting only one complete reciprocation for each crankshaft revolution. In this example 29 again represents an inlet port and 31 an exhaust port in the sleeve-valve cylinder. As opposed thrusts are applied along the connecting rods 15 (as indicated by the arrows) the resultant thrust on the sleeve 13 (in an axial direction) will be very small.

Here again the outer face 33 of the sleeve-valve cylinder is adapted as a pump for generating a suitable air pressure for supply to the inlet of the engine.

In this example, there is a diametrically-opposite piston and sleeve-valve cylinder (not shown) respectively connected by the connecting rods 15b to lugs at the opposite ends of the sleeve 13 and diametrically opposite the lugs to which the connecting rods 15 are connected. The two sleeve-valve cylinders, it will be observed, are reciprocated 180° out of phase, as are also the two pistons 16, an arrangement which is very applicable to a flat twin.

The construction of Figure 5 has much in common with that of Figure 4 except that here the connecting rods 15 and 15b are forked at their radially-inner ends and connected in pairs to pairs of trunnions 35 at opposite ends of the sleeve 13, this arrangement also being very applicable to an opposed twin construction or more particularly to a flat multi-cylinder arrangement with two banks of in-line cylinders, only the middle cylinder of one bank being shown in detail.

The inclined pins 11 of the crankshaft 12 will be mounted at different inclinations to one another as necessary to give a desired firing order.

What I claim as my invention and desire to secure by Letters Patent of the United States is:

1. A fluid-pressure engine having a ported cylinder, a piston coating therewith, one of the members being reciprocable with respect to the other, and a Z-type crankshaft, the axes of the said one member, of the crankshaft, and of the inclined pin thereof, all meeting at a point.

2. A fluid-pressure engine having a Z-type crankshaft, a ported cylinder with its axis extending radially of the crankshaft axis, a piston coating with said cylinder, and a sleeve journalled on the inclined pin of the crankshaft, one of said coating members being connected to said sleeve so as to be reciprocated with respect to the other coating member on the rotation of the crankshaft, the axes of the reciprocating member, of the crankshaft and of the inclined pin thereof, all meeting at one point.

3. A fluid-pressure engine having a Z-type crankshaft, a ported cylinder with its axis extending radially of the crankshaft axis, a piston coating with said cylinder, and a sleeve journalled on the inclined pin of the crankshaft one of said coating members being connected to one end of said sleeve so as to be completely reciprocated once for each crankshaft revolution, the axes of the reciprocating member, of the crankshaft and of the inclined pin thereof, all meeting at one point.

4. A fluid-pressure engine having a Z-type crankshaft, a stationary piston with its axis extending radially of the crankshaft axis, a sleeve journalled on the inclined pin of said crankshaft and a ported cylinder coating with said piston and connected to said sleeve so as to be reciprocated on rotation of the crankshaft, the axes of the cylinder, of the crankshaft and of the inclined pin thereof, all meeting at one point.

5. A fluid-pressure engine having a Z-type crankshaft, a sleeve journalled on the inclined pin of the crankshaft, radially-extending ported cylinders with piston therein, and connecting rods by which each piston and cylinder are connected to spaced points of the sleeve so as to be reciprocated out of phase during rotation of the crankshaft, the axes of the reciprocating members, of the crankshaft and of the inclined pin thereof, all meeting at one point.

6. A two-stroke internal-combustion engine, according to claim 4, in which the radially-outer end of the cylinder serves as an air pump.

7. A two-stroke internal-combustion engine, according to claim 5, in which the radially-outer end of the cylinder serves as an air pump.
